SAMPLE CARRIER

Harry L. Hoenigsberger, Chicago, Ill.

Application October 1, 1938, Serial No. 232,738

2 Claims. (Cl. 129—1)

This invention relates to an extension sample carrier which is especially designed for the display of fabrics of various kinds, and the carrier is so designed that the fabric samples may be easily inserted, or removed and rearranged within the carrier as occasion may require. The carrier is also designed in such a way as to protect the samples and permit the carrier to be readily transported from place to place and conveniently used in such a way as to afford an attractive display of a large number of samples which may be either retained within the carrier or quickly removed therefrom where removal is desired for critical investigation as to color, texture, or otherwise.

The carrier furthermore makes provision for the neat and orderly arrangement of the samples and for the convenient storage of the carrier when not in use, and also provides for indefinite extension to accommodate any desired number of samples within the confines of the covers. Further objects and details will appear from a description of the invention in conjunction with the accompanying drawing, wherein,

Figure 1 is a perspective view of the sample carrier of the present invention;

Fig. 2 is an enlarged sectional elevation partially broken away in the center and taken on line 2 of Fig. 1;

Figs. 3 and 4 are sectional details showing the means provided for attaching the handles to the upper supporting bars of the carrier;

Fig. 5 is a detail partially in section showing the method of supporting the extension posts upon which the samples are mounted; and

Fig. 6 is a perspective of one of the samples removed from the carrier.

The carrier of the present invention comprises outer covers 10, of rectangular shape and of a size slightly larger than the dimensions of the intended samples 11, so that when the samples are inserted the edges of the covers will overlap the edges of the samples and afford protection therefor. The covers are preferably of somewhat flexible or limp material, such as genuine leather, fabric leather, cardboard, fiberboard, or cloth, which may be covered with a finishing surface of paper or fabric, or other similar material. Since the covers and their means of connection are duplicated on each side of the carrier, the description of one will suffice for both.

Each of the covers at its upper edge terminates in a loop or fold 12 which supports a pintle rod 13 which at recurrent intervals is embraced by a hinge sleeve 14 connected by a neck 15 with

a tubular metallic bar 16 of flattened rectangular shape which is surrounded by a sheath or covering 17 of leather, fabric or other material harmonizing with the material from which the covers are constructed. This arrangement affords a stiff unyielding bar from which the cover section is suspended and upon which it is hinged to afford easy and convenient access to the interior of the carrier, since the hinge permits the cover section to be turned completely back and away from the samples, and the covers being somewhat limp will easily flex or fold back to the desired extent.

Each of the tubular bars, at points equidistant from the center, is surrounded by a bracket loop 18, the upper ends 19 of which are brought together to afford attaching tongues for the ends of a handle section 20 of inverted U-shape formation. Each handle section is preferably formed of leather or similar material, which is looped or of double ply thickness as indicated in Fig. 3, and throughout the gripping portion of the handle section, a packing or wadding 21 is provided which fills out the handle section to the extent required to afford a convenient gripping surface. The inner edges 22 of the handle section are united by stitching or the like, and at the lower ends 23 of the handle section the material is extended inwardly to embrace the attaching tongues 19 and connected thereto by rivets 24, which afford a firm, rigid and convenient means for securing the handle sections. The two handle sections formed and united as above described are of sufficiently flexible formation to permit them to be brought together for gripping purposes, as indicated in dotted lines in Fig. 2.

One of the tubular bars 16, which may be regarded as the rear bar, is provided on its interior with a reinforcing plate 25, as shown in Fig. 5, which is provided near each end with a threaded aperture 26 which is adapted to receive the reduced threaded end 27 of a post 28 upon which the samples 11 are threaded. The post 28 is provided in its outer end with a threaded recess 29 which is adapted to receive the reduced threaded end 30 of an extension post 31. Additional extensions may be provided in like manner to accommodate the desired number of samples.

Each of the samples is provided near its upper edge with an aperture which is protected by a grommet 32, and as shown each sample of full size is supplemented by swatches 33 of smaller

size intended to display various color tones of the material composing the principal sample.

The upper ends of the posts 28, or extensions 31 as the case may be, are entered through apertures 34 in the forward tubular supporting bar, and are held in locked relation therein by means of a sliding lock bar 35 which may be manipulated by a button 36 outwardly projecting through a slot 37, the arrangement being such 10 that when the locking bar is thrown in one direction it will engage and lock against the posts, and when thrown in the other direction will release the same.

The free lower edges of the covers 10 may be 15 secured together by a strap 38, which as shown is secured by rivets 39 to the rear cover, and is adapted to be engaged by a buckle 40 secured by a loop 41 to the lower edge of the front cover.

In use, a pair of posts, with or without extensions, will be screwed into the supporting posts of the rear cover, after which the desired number of samples will be threaded upon the posts and the front cover will be secured in place and locked thereon. If it becomes necessary to increase the number of samples, additional post sections may be supplied if desired, which permits the samples to be increased or reduced in number, or to be rearranged or individually removed as occasion may require. With the samples properly arranged, the carrier will be strapped at its lower end and may be easily carried by the handles, which being secured to the supporting bars and flexed inwardly to the center will always suspend the carrier evenly and uniformly regardless of the thickness of the carrier and irrespective of any increase or diminution in the number of the samples. Furthermore, by forming the handle in sections each of which is secured to a supporting bar in the manner described, the interior of the carrier will be 40 unimpeded by the presence of the handles, which is a much superior arrangement to one which might employ the posts as points of connection for handles or the like, and by locating the handles at the upper or closed end of the carrier the samples will hang downwardly from the points of suspension, which tends to keep them straight and in an orderly condition, and prevents them from becoming mussy or compacted 45 within the carrier, which might occur if the handles were located at the open or free ends of the covers.

The samples may be shown in the carrier by unstrapping the bottom end and turning the 50 top cover back at the hinge; the samples can then be turned back one at a time so that they

can be inspected with the swatches attached to them. If it is necessary, for sales or display purposes, the cover can be easily removed by unlocking the same and the samples can be lifted off the posts for exhibition or matching purposes. When finished, the samples are simply placed back on the posts and the carrier becomes a solid unit as before.

Although the invention has been described with particularity as to detail, and although the device, constructed as shown, embodies the features of the present invention in their preferred form, it is not the intention, unless otherwise indicated, to limit the claims to the details of construction shown, since variations therein may be made without departing from the spirit of the invention.

I claim:

1. In a sample carrier, the combination of front and rear covers, a stiff supporting bar for the upper edge of each of the covers and having a hinge connection with the associated cover, binding posts adapted to suspend samples and mounted upon one of the supporting bars and extending through the other supporting bar, means for locking the last mentioned supporting bar, means for locking the last mentioned supporting bar to the binding posts, a U-shaped handle section for each of the supporting bars, and a connection for each end of each handle section in the form of a loop encircling the supporting bar and terminating in outwardly extending tongues having the ends of the handle section secured thereto, the handle sections being adapted to flex inwardly to afford a medial support for the carrier.

2. In a sample carrier, the combination of front and rear covers, a stiff supporting bar for the upper edge of each of the covers and having a hinge connection with the associated cover, binding posts adapted to suspend samples and mounted upon one of the supporting bars and extending through the other supporting bar, means for locking the last mentioned supporting bar to the binding post, a U-shaped handle section for each of the supporting bars, and a connection for each end of each handle section in the form of a loop encircling the supporting bar and terminating in outwardly secured tongues having the ends of the handle section secured thereto, the handle sections being adapted to flex inwardly to afford a medial support for the carrier and a strap for securing the free ends of the covers.

HARRY L. HOENIGSBERGER.
